UNITED STATES PATENT OFFICE.

WILLIAM H. LEWIS AND HUBERT LEE LITTELL, OF INDIANAPOLIS, INDIANA.

VEHICLE-SPRING.

SPECIFICATION forming part of Letters Patent No. 625,176, dated May 16, 1899.

Application filed July 8, 1898. Serial No. 685,384. (No model.)

To all whom it may concern:

Be it known that we, WILLIAM H. LEWIS and HUBERT LEE LITTELL, citizens of the United States, residing at Indianapolis, in the 5 county of Marion and State of Indiana, have invented certain new and useful Improvements in Vehicle-Springs; and we do declare the following to be a full, clear, and exact description of the invention, such as will enable 10 others skilled in the art to which it appertains to make and use the same, reference being had to the accompanying drawings, and to the letters of reference marked thereon, which form a part of this specification.

15 Our invention relates to the class of springs that are employed in supporting the body of a vehicle upon the axle or running-gear and in similar applications, such as supporting a seat; and it consists in a spring of new and 20 novel construction and arrangement of elements whereby a spring is produced from inexpensive material and by simple means and embodying the advantages of an elliptical form, but capable of use in more limited space, 25 as will be hereinafter more fully described and claimed.

Our object is to provide a spring which may be constructed at the lowest possible cost and which shall be adapted to displace the more 30 complicated built-up elliptical spring, which is expensive both to construct and maintain and which suffers from corrosion between the plates, necessitating frequent repainting.

Another object is to provide such a spring 35 as when finished shall consist of but a single piece whose various members are formed continuously and practically integrally one with another, thus dispensing with separate connecting devices.

40 A still further object is to provide a spring of this character which shall provide the maximum flexibility in the minimum operating space.

These objects are attained in our invention, 45 which is adapted to many situations, and is economical and durable in use, while the form is so simple that the spring may be reset and tempered in the ordinary shops.

Referring to the drawings, Figure 1 represents 50 an elevation of our spring, illustrating

its operative position in relation to a carriage-axle and body-spring bar; Fig. 2, an elevation of the spring detached; Fig. 3, a top plan view of the spring, and Fig. 4 an elevation of the two parts of which the complete spring is 55 composed.

In construction we form a spring A to conform to the general shape of elliptical springs, so as to be applicable to vehicles as usually constructed, in which is an arched member A², 60 having a reinforced central portion D adapted to support the load, and an inverted arched member A³, having a reinforced central portion E providing a bearing whereby the spring and load are supported. Fig. 1 illustrates the 65 manner in which the spring may be connected operatively in this case to an axle B of a carriage by clips d and at the top to the spring-bar C by clips b. In small sizes a hoop may first be formed and then twisted to the form as shown 70 in Figs. 2 and 3, and the enlarged or reinforced parts D E produced by overlaying and welding on a sheet of metal or section of split tube of suitable length. In all cases the ends a a of the arch A² when complete extend below the 75 ends e e of the inverted arch A³ and bend in a reversed curve toward each other, so as to intersect and join in a curve F, thus permitting of the greatest length of arch with the greatest degree of radius of the arches, thereby 80 avoiding undue spreading of the central bearings D E. The central bearing-points preferably lie in two parallel vertical lines, although they may be in the same line one 85 above the other in some cases, the upper and lower members, as at G H I J, crossing either to the right or to the left, but preferably in a somewhat short transverse curve, as shown in Fig. 3, to meet centrally in the curve or semicircle F.

In attaining the full advantages of our invention we may employ bar-steel having a "round" or circular cross-section—semicircular cross-section; or we may use the tubular form, either circular in cross-section or semicircular, as well as a tube flattened and rolled in upon itself at one side, so as to be of double thickness throughout and semicircular in cross-section, and the latter, when reinforced 95 with a suitable distance at D E, by means of a 100

solid bar inserted and welded in, provides a
spring embodying the advantages of one having
multiple leaves or plates, but presents no
openings to receive moisture and eject corrosive
stains.

In some cases in advantageously manufacturing our spring we employ two pieces and bend each so as to form two halves, each comprising a portion of both the arch and inverted arch integrally joined and twisted so as to form the curved ends F F. Then the ends h i are lapwelded, and the ends m n are likewise lapwelded, the overlapping being carried to any desired length so as to provide suitable reinforcement at the bearing-points. Instead of lapwelding the ends may abut within a section of tube, the whole being welded together, and, if desired, forged into any desired rectangular form in cross-section. After completing the spring it may be tempered by any suitable process.

While we prefer to construct our spring in the manner shown and described, we reserve the right to join the ends of the several operative members at other points, the essential characteristics being that the completed spring shall be continuous in its parts or having its members formed integrally and the spring-points of the arches relatively situated and connected, as shown and pointed out.

One of the obviously important advantages of our invention consists in the adaptation of bar-steel or tubular forms having an even diameter or thickness, requiring no special forging or dressing nor machine-work separate from the act of welding at the indispensable joints, the bending being but a simple and inexpensive operation.

Having thus described our invention, what we claim as new, and desire to secure by Letters Patent, is—

1. A vehicle-spring consisting of two half-elliptical metallic springs each of which is composed of two segments of an arc connected in an overlapping welded joint to reinforce the bearing-point or center of the half-elliptic and the ends of which half-elliptical springs are joined in pairs integrally, whereby a spring is formed having a continuity of metal without moving joints or detachable parts, substantially as set forth.

2. A vehicle-spring composed of two parts each of which is suitably bent at the center to form the ends of a double elliptic spring and the ends of which two parts are joined rigidly in pairs by welding to form the bearing parts whereby a double elliptic spring is formed having a continuity of metal throughout without movable joint or detachable part, substantially as shown and described.

3. A vehicle-spring composed of two parts whose ends are overlapped and rigidly joined by welding to form the bearing parts or seats of a double elliptic spring and whose central parts are twisted and bent to form the ends of a double elliptic spring, the whole having a continuity of metal throughout, substantially as set forth.

4. An elliptical spring composed of two oppositely-disposed arched members each of which is formed of two parts overlapped at the ends and rigidly joined by welding to form the center of the arch and bearing-seat and whose end portions are formed integrally one with the other at the center of each of said two parts in the form of a loop, substantially as shown and described.

5. An elliptical spring having counterpart arched members each of which is formed of two parts and oppositely disposed and rigidly joined at the center of each arch by welding to form the bearing parts whose diameter is greater than the other portions, the centers of which two parts are bent to form integrally-connected ends of the said counterpart arched members, substantially as set forth.

6. The herein-described spring consisting of the oppositely-disposed arched members A² and A³ formed of two parts having uniform diameters and rigidly joined and reinforced by welding at the crowns D and E respectively and having the spring ends formed integrally by bending said two parts at their centers, substantially as shown and described.

In testimony whereof we affix our signatures in presence of two witnesses.

WILLIAM H. LEWIS.
H. LEE LITTELL.
